PROCESS FOR STABILIZING THE FLAVOR
AND ODOR OF FATTY MATERIALSEddy W. Eckey, Wyoming, Ohio, assignor to The
Procter & Gamble Company, Cincinnati, Ohio,
a corporation of OhioNo Drawing. Application August 22, 1932,
Serial No. 629,887

13 Claims. (Cl. 99—11)

This invention relates to the treatment of fats and oils for the purpose of improving odor and flavor, particularly stability of same.

Almost any fat or oil of good quality either 5 is of pleasant and mild odor and flavor without special treatment or can be brought to such a condition by suitable processing, particularly steam deodorization. However, oils and fats on exposure to air tend to become oxidized, and 10 such oxidation quickly causes development of an inferior flavor, and eventually may result in extreme rancidity.

It has already been proposed to stabilize fatty materials against oxidation and resulting changes 15 in odor, flavor, etc., by incorporating therewith certain organic or inorganic acids. Particular reference is made to my copending application Ser. No. 629,891, filed August 22, 1932, which discloses desirable antioxidant effects obtained, 20 for instance, by use of less than .01 per cent of phosphoric acid. In application Serial No. 627,- 618, filed Aug. 5, 1932, Richardson, Vibrans, and Andrews have disclosed the preparation as antioxidants of the group of compounds comprising 25 inorganic acids containing stably bound oxygen (i. e., contain oxygen but are not themselves strong oxidizing agents) and their acid salts or esters. Various organic acids have also been proposed for use as antioxidants in fatty ma- 30 terial, for example, tartaric acid.

The present invention provides an improved process for using acid antioxidants on fatty materials, without claiming the acid antioxidants as such, since any one of the acid antioxidants 35 for fatty material will, when used according to my invention, provide the advantages to be described. My objects are to provide a safe and convenient method for contacting oil and antioxidant, and also to obtain even greater im- 40 provement in the stability of the fatty material than is obtained by the simple addition of antioxidant alone.

Briefly stated, my process consists of treating fatty material simultaneously with a powdered 45 solid and an acid antioxidant. In its preferred form, the process is carried out by first adding a substantial proportion of an acid antioxidant to a pulverulent material and then agitating this mixture with the oil or fat after the latter has 50 been deodorized with steam and cooled to about 150° C. or lower. My process may also be carried out immediately following, during, or preceding deodorization and may also be used to advantage on undeodorized fats, in which cases the common 55 bleaching treatments, if any, should ordinarily

precede treatment by my process. Exception to this last rule may arise when my process is used to stabilize fatty materials during storage other than temporary storage prior to deodorization, but even in such a case it is desirable to apply my 60 treatment again at some stage following the customary bleaching treatment, preferably after deodorization.

Protection of the oil from air during the stabilizing treatment is desirable and may be secured, 65 for instance, by use of a vacuum or a blanket of inert gas. Agitation may be effected by any known means, steam agitation being quite satisfactory if the process is carried out under vacuum.

The pulverulent material is preferably of an absorbent nature. It should be substantially inert chemically towards acids or fatty materials. It may or may not have bleaching properties toward fatty material. For instance, kieselguhr, 70 bleaching carbon, inactive carbon, fuller's earth and other siliceous minerals are suitable for use in my process. Powdered solids which have been previously acid treated and washed are particularly suitable, because thereby the tendency toward 75 further reaction with impregnating acid is eliminated or greatly diminished. Pulverulent materials which react chemically with the acid antioxidant or with the oil should, of course, not be used.

I prefer to use orthophosphoric acid, but organic acid antioxidants or other inorganic acids of the class described above, such as sulfuric acid and metaphosphoric acid, may be used. The acid may be partially neutralized before use, and may thus consist of acid salt, such as primary sodium phosphate, but the acid salts are not in general so effective as the original acids from which they are derived.

The proportion of acid to kieselguhr or other solid may vary within wide limits. Ordinarily I use not less than 5% acid in the treating mixture, but may use less, especially when the pulverulent material is desired as a filter-aid independent of its use for stabilizing the fatty material in accordance with my invention. Any proportion of acid may be conveniently used up to the amount that causes lumping of the solid material and consequently retards distribution of the treating mixture throughout the fatty material. In general, 5 to 20% acid in the treating material is my preferred range, but my invention is by no means limited to exactly this range.

The proportion of treating material to oil or fat may likewise vary within wide limits. It is 110

seldom advisable to use more than one part of the treating mixture to 1000 parts of fatty material, but my invention may be practiced with even a larger proportion. In general I prefer to 5 use in the neighborhood of one part of the treating mixture to 10,000 parts of fatty material.

While bleaching materials such as carbon and fuller's earth are convenient forms of powdered solids for use in my invention, it should be understood that any bleaching action which they exert 10 during the carrying out of my process is purely incidental and negligible in comparison with the stabilizing effect of the process. This will be the more readily understood when it is remembered 15 that the maximum amount of treating material required in my process is rather less than the minimum amount of absorbent bleaching material heretofore used in the treatment of oils and fats for decolorization.

20 Instead of premixing the mineral acid with solid material as described above, my invention may be alternatively carried out by adding the acid and solid material separately to the fatty material to be treated.

25 The fatty material containing the treating mixture is filtered at a suitable temperature in accordance with conventional methods or otherwise processed so that all or practically all of the solid material is removed. Owing to the 30 minute amount of acid used relative to the fatty material, it is difficult to describe accurately what happens to the acid during the process. Apparently it reacts at least in part with impurities in the oil and is held by the surface of the solid material.

35 Regardless of the correctness of the above explanation, I have found that the process herein described results in an even greater improvement in the quality of the fatty material treated than is obtained by the use of acid antioxidants alone. The improvement is many fold greater than can be obtained merely by filtering the fatty material, or by merely filtering it with kieselguhr, carbon, or the like.

40 *Example:*—7 parts of syrupy phosphoric acid and 93 parts of kieselguhr are mixed together until the mixture has approximately the free flowing properties of the original kieselguhr. This powder is then mixed with freshly deodorized refined cottonseed oil in a closed tank mechanically agitated at 100° C. After cooling to 60° C., the oil is filtered. After exposure to air, the flavor of this oil is very much better than that of the same oil not similarly treated.

45 Other vegetable oils, including those processed as salad oils, hydrogenated vegetable shortenings, and lard substitutes of the type commonly called "Compound", also various animal fats including unbleached and undeodorized prime lard, show 50 similar improvement in varying degree when treated according to the process described herein.

Having thus described my invention, what I claim as new and desire to secure by Letters 55 Patent, is:

60 1. The process of treating fatty materials to stabilize odor and flavor which comprises mixing therewith substantially inert pulverulent material and acid having antioxidant properties toward fats, and thereafter removing at least the major portion of pulverulent solid from the fatty material.

65 2. The process of treating fatty materials to stabilize odor and flavor which comprises mixing

therewith pulverulent absorbent bleaching material having no chemical action towards acids or said fatty materials and acid having antioxidant properties toward fats, said treatment being subsequent to any of the usual bleaching treatments that may be required for decolorizing said fatty material, and thereafter removing at least the major portion of pulverulent absorbent bleaching material from the fatty material.

80

3. The process of treating fatty materials to stabilize odor and flavor which comprises mixing therewith after deodorization substantially inert pulverulent material and acid having antioxidant properties toward fats, and thereafter removing at least the major portion of pulverulent material from the fatty material.

85

4. The process of treating fatty materials to stabilize odor and flavor which comprises simultaneously mixing therewith during deodorization substantially inert pulverulent material and acid having antioxidant properties toward fats, and thereafter removing at least the major portion of pulverulent material from the fatty material.

90

5. In the processing of fatty material, the step which comprises simultaneously mixing therewith prior to storage substantially inert pulverulent material and acid having antioxidant properties toward fat.

100

6. The process of stabilizing the odor and flavor of fatty materials which comprises treating same with substantially inert powdered solid mixed with acid having antioxidant properties toward fat.

105

7. The process of stabilizing the odor and flavor of fatty materials which comprises treating same with pulverulent absorbent bleaching material having no chemical action towards acids or said fatty materials mixed with acid having antioxidant properties toward fat, said treatment being subsequent to any of the usual bleaching treatments that may be required for decolorizing said fatty material.

110

8. The process of stabilizing the odor and flavor of fatty materials which comprises treating same after deodorization with substantially inert pulverulent material mixed with acid having antioxidant properties toward fat.

115

9. The process of stabilizing the odor and flavor of fatty materials which comprises treating same during deodorization with substantially inert pulverulent material mixed with an acid having antioxidant properties toward fat.

120

10. In the processing of fatty material, the step which comprises treating same prior to storage with substantially inert pulverulent material mixed with an acid having antioxidant properties toward fat.

125

11. The process of stabilizing the odor and flavor of fatty materials which comprises treating same with a mixture of acid having antioxidant properties and substantially inert pulverulent material previously acid washed.

130

12. The process of stabilizing the odor and flavor of fatty material which comprises treating same with substantially inert pulverulent material mixed with more than 5 percent of an acid having antioxidant properties.

135

13. The process of stabilizing the odor and flavor of fatty material which comprises treating same after deodorization with a mixture of substantially inert pulverulent material and phosphoric acid.
